UNITED STATES PATENT OFFICE.

ALFRED RANDOLPH, OF SALEM, OHIO, ASSIGNEE TO THE DEMING COMPANY, OF SALEM, OHIO, A CORPORATION OF OHIO.

POWER-PUMP WORKING HEAD.

Application filed August 24, 1925. Serial No. 52,163.

This invention is concerned with pumps, and more particularly, with power heads for deep well pumps, and the general object of the present invention is to provide a compact self-lubricating power head, having the operating mechanism thereof arranged in a compact manner to embody a pitman which will have a substantially direct thrust upon the pump rod, whereby the reacting forces of the crank motion and undesirable overhanging of the connections between the power head and the pump rod may be reduced to a practical minimum.

A further object of the present invention is the provision of an encased power-head which may have the operative parts thereof arranged in such a manner as to afford simplicity in the production operations of manufacturing the power head and which manufactured structure will have the characteristics of durability and dependability under unfavorable operating conditions. A still further object of my invention is the provision of a novel casing structure which may serve as a frame for a power head mechanism and a lubricant retaining casing which may function in the distribution of the lubricant to the operating parts of the power head.

Other objects of my invention will be hereinafter set forth in the following description referring to the accompanying drawings which illustrate a preferred form thereof. The essential characteristics are summarized in the claims.

In the drawings, Fig. 1 is a side elevation of a pump and power head therefor; Fig. 2 is a cross-sectional elevation taken through the power head and an interconnecting mechanism between the power head and pump proper; Fig. 3 is a cross-sectional elevation taken substantially along the line 3—3 of Fig. 2; Fig. 4 is a cross-sectional detail taken along the line 4—4 of Fig. 2 at the top of the power head casing; Fig. 5 is a similar cross-sectional detail taken substantially along the line 5—5 of Fig. 2; and Fig. 6 is a perspective of a cross head.

There are a variety of forms of power heads, particularly adaptable to the operating of deep well pumps, embody-

ing various features which are directed to the preservation of the pump when in rural use, but these various protective features, when incorporated in the powerhead structure, usually result in greatly increasing the manufacturing cost of the power head.

My invention contemplates the provision of a powerhead, embodying a minimum number of operating parts, arranged in a novel manner, whereby these parts may be light in weight, yet extremely sturdy in construction, and this arrangement incorporates therein as an essential feature thereof, a housing or casing, comprising a frame for the operating parts and also comprises a lubricant retainer. My arrangement of the operating parts, as I will hereinafter set forth, affords a maximum application of power from the pitman to the pump rod. To obtain this result, the pitman is arranged to actuate a flat slide, operating directly on the casing and the pitman moves in a path lying in a plane extending parallel to the slide and pump rod motion. The operating parts are disposed within or on the casing in such a manner that both a submerged and gravity lubricating action is available to insure a constant lubrication of the parts.

In the drawings, I show in Fig. 1, a powerhead generally designated by the reference P, mounted on a base 10, which also comprises a support for a driving motor 11. The powerhead is connected to a pump rod 12 and suspended from the base, are rods or pipes 14, supporting an underground discharge head 15. The powerhead as shown in Fig. 1, is adapted to also operate a piston rod 16, carrying, in the lower end thereof, an air piston disposed in the air cell 17, mounted in the discharge head 15. This general arrangement is adaptable for underground discharge to a connection afforded at 20 on the discharge head 15. The powerhead, as shown in Fig. 2 is also adapted to operate a surface discharge deep well pump, in which case, the discharge head 15 is mounted directly at the base of the powerhead casing as shown in Fig. 2.

The operating parts of the powerhead may comprise a drive shaft 24, suitably mounted on removable oil retaining bearings 25 and

26, carried by the sump member 28 of the casing. The bearings are located at the upper part of the sump member to afford proper ground clearance for a driving member, such as a chain gear or pulley 30 rigidly mounted on an extension of the shaft 24 exteriorly of the sump member. The shaft 24 carries a pinion 32 rigidly mounted therein and meshing with a crank gear 33, which is rigidly mounted on a reduced bearing portion 34^a of a double bearing crank member 34. As shown in Fig. 2, the two arms of the crank loosely bear on removable stud members 36 and 37, extending through suitable borings formed in the sump member 28. A pitman 40 is operated by the crank 34 and has the upper end thereof loosely connected to a pin 41, rigidly mounted on a slide member 42.

29 The slide member 42 may extend a substantial distance upwardly and downwardly from the pitman connection and may slide in a slideway formed on an upper casing member 44. This upper casing member 25 may have the front wall thereof slotted from the bottom to the top thereof and a slideway 45 is formed along the margins of the slot formed in the casing. Slide plates in the form of Z-shaped rails 46 may overhang 30 the surfaces of the slide member 42 to retain it in slidable operative position in the slideway. The slide member 42, it will be seen, is preferably disposed substantially exteriorly of the casing and the formation of the 35 upper casing member 44 and the sump casing member 28 is such that the slide is operated vertically, with those operative surfaces thereof and of the slideway requiring lubrication disposed in planes lying within the 40 confine of the front wall boundary of the sump member 28. In other words, the sump member, in front thereof immediately beneath the slide and the slideway of the upper casing member is extended outwardly to receive all oil draining or dripping from the 45 slide and slideway, thus preventing oil leakage into the pump or well. This arrangement is clearly seen in Fig. 2. The slide member 42 is provided with an extension or lug 43 to which the pump rod 14 may be attached in any suitable manner. The connection for the air piston rod 16 may comprise an arm 48, suitably connected to the slide and piston rod 16.

50 From the foregoing description, it will be seen that the casing is formed primarily by two members, one mounted upon the other and that the lower casing member 28 serves as a support for the crank shaft studs and drive shaft. It will be apparent that the machining operations of the parts in the course of manufacturing, may be very economically effected.

55 Upon assembling the operating parts 60 within the casing, the pitman 40, crank 34

and crank gear 33, may be first assembled as a unit and then placed within the sump casing 28. The crank shaft studs 36 and 37 may then be inserted in the crank bores.

The bearing 26 of the drive shaft may 70 then be mounted on the casing and the drive shaft with the pinion 32 thereon may be inserted within casing bore formed to receive the bearing 25. The bearing 25 may thereafter be assembled. The upper casing member 44 may have the slide and the slideway members assembled thereon with the exception of the final positioning of the pin 41. The upper casing member may then be placed upon the lower casing member and the pitman connected to the slide by the proper positioning of the pin 41. The pin 41 may thereafter be retained in adjusted position by any suitable means such as a 80 lock screw 41^a, threaded in the slide member 42. To facilitate inspection of the operating parts and adjustment thereof in the assembly, an opening is formed in the casing member 44 which is closed by a door 44^a.

It will be noted that the sump casing member 28 is preferably formed as an integral part around all sides thereof with the exception of the top and the bores formed therein to receive the driving shaft bearings and the crank studs. By properly fitting the crank studs to prevent oil seepage, the sump member may be filled with lubricant to a level which is slightly below the drive shaft bearings. The lower end of the pitman where it is connected to the crank and the crank arm bearings and the gears are thus constantly lubricated.

To effect proper, thorough and constant lubrication of the slide member and the pitman connection thereto, I provide an oil reservoir preferably formed within the casing member 44 at the top thereof as shown at 50 (see Fig. 2) to which oil is elevated through an upwardly extending pipe line 52 extending through the casing wall as shown in Fig. 4 to discharge at the middle of the oil reservoir. The pipe line 52 may be connected to an oil pump casing 53 submerged in the lubricant contained by the sump member 28. The member 53 may be 105 secured to an interiorly disposed lug formed on the front wall of the sump member by any suitable means such as a bolt 53^a. Thus, I show, in Fig. 3, a simple and convenient mechanism in association with the pump member 53 which may comprise a pump plunger 54 reciprocating in a suitable bore formed in the oil pump member 53 and operated by an eccentric 55 preferably formed directly on the hub 34^b of the crank arm. Openings 70 are formed in the oil casing to be disposed at the end of the plunger when the same is in its uppermost position. A vacuum is formed during the upward stroke of the plunger and when the openings 70 110

110

115

120

125

130

135

are uncovered the oil is drawn into the cylinder. A spring 56 serves to operate the plunger upwardly and the eccentric operates the plunger downwardly on the force stroke.

5 A ball check valve is shown at 57 (see Fig. 3) to check the back flow of the oil into the line 52 when the plunger is operated by the spring.

The disposition of the reservoir 50, as will 10 be seen in Fig. 2, is such that the oil flow therefrom, through openings 45^a formed in the front wall of the upper casing member, will spread directly on the slideways 45 and consequently upon the slide operating surfaces.

15 A cap member 62 is provided to close the top of the reservoir and casing member 44. This cap may overhang the slideway and depending from the cap 62 may be a flat member 63 which will prevent splashing 20 of the lubricant by the slide member 42 when it is at the uppermost reaches of its reciprocatory motion. The pitman 40 is provided with an oil hole 40^a in its upper hub where it is connected to the pin 41,

25 which may be substantially aligned with a small opening 50^a formed in the bottom wall of the reservoir 50 whereby a constant dropping or flow of the oil from the reservoir will effect lubrication of the pin 41 and the 30 upper end of the pitman. From the foregoing description of my invention, it will be seen that I provide a very compact power head adaptable to the driving of a deep well pump of either the underground or

35 surface discharge type. All parts of the operating mechanism are either completely submerged in lubricant or constantly lubricated by a gravity flow of the lubricant from the reservoir. The operating parts are 40 housed by an enclosing casing which serves to support the operative parts as well as to retain the lubricant and exclude extraneous matter. The arrangement of the parts is such that the pitman may be connected to a 45 vertical reciprocating slide or cross head in balanced relation to the pump rod connection with a slight overhang between the pump rod, cross head and pitman, thus insuring maximum direct application of power from

50 a double bearing crank to the pump rod upon the up or working stroke thereof. While the mechanical characteristics of the operating parts is such as to assure long efficient operative life, these parts may be of comparatively light construction, thus greatly decreasing the manufacturing and merchandizing cost of the parts. The crank is provided with double bearing arms and this double bearing feature is incorporated in 55 such a manner in the general arrangement of parts, as to not interfere with the compactness thereof.

I claim:

1. In a power head of the character described, the combination of a casing, a crank

within the same, said casing having an upward extension, a slideway on the exterior of said extension, a slide mounted on the slideway, a wrist pin carried by the slide and extending inwardly through a slot in 70 the casing, a pitman mounted at one end on the crank and at the other end on the wrist pin, said pitman and slide operating in parallel planes, means for connecting a pump rod to the slide, a gear on the crank shaft 75 within the casing, and a driving shaft parallel with the crank shaft and having a pinion meshing with the gear.

2. In a power head of the character described, a reciprocally operable slide member adapted to be connected to a deep well pump rod, a pitman for operating the slide, a crank mechanism for operating the pitman, a casing structure enclosing said pitman and operating mechanism, said casing having a vertical slideway formed exteriorly thereof along which the slide operates, said slideway being disposed to drain into the lower part of the casing.

3. In a power head of the character described, a reciprocally operable sliding member adapted to be connected to a deep well pump rod and a pitman for operating the slide, a crank mechanism for operating the pitman, a casing structure enclosing said pitman and operating mechanism, said casing having a slideway formed exteriorly thereof along which the slide operates and having an opening extending vertically along the slideway to afford passage for a connection 100 between the pitman and slide.

4. In a power head of the character described, a reciprocally operable sliding member adapted to be connected to a deep well pump rod and a pitman for operating the slide, a crank mechanism for operating the pitman, a casing structure enclosing said pitman and operating mechanism, said casing having a slideway formed exteriorly thereof along which the slide operates and an oil 105 reservoir formed at the top thereof for providing slideway lubrication.

5. In a power head of the character described, a crank member, means for driving the crank member, a pitman, a vertically 115 movable slide operated by the pitman, a casing comprising two members, one member comprising a support for the crank mechanism, the other member being mounted on the first member and having its front 120 wall set back from the wall of the first member and having a slideway located above the projecting portion of the first member, the crank casing comprising an oil sump and the slide supporting casing comprising 125 an oil reservoir for lubricating the slide by gravity feed.

6. In a power head of the character described, a crank member, means for driving the crank member, a pitman, a vertically 130

movable slide operated by the pitman, said slide being mounted on the exterior of the casing and having an inwardly extending wrist pin which the pitman embraces, a casing comprising an upper and a lower housing, the lower member comprising a support for the crank mechanism and the upper member comprising a slideway for the slide, said slideway terminating at the bottom thereof behind the front wall boundary of the lower casing member and there being an opening through the top of the lower casing registering with the slideway.

7. In a power head of the character described, a crank member, means for driving the crank member, a pitman, a vertically movable slide operated by the pitman, a casing comprising an upper and a lower member, the lower member comprising an oil sump and a support for the crank mechanism, the upper member comprising a support for the slide and having an oil reservoir formed adjacent the top thereof and means for forcing the oil from the sump to the reservoir.

8. In a power head of the character described, a crank mechanism, a pitman operated thereby, a slide actuated by the pitman, a casing supporting said slide and enclosing said pitman and operating mechanism, said casing having an oil reservoir formed at the top thereof with spillways leading to the path of the slide and to the pitman connection between the pitman and side, the lower part of the casing comprising an oil sump and formed to receive oil drippings from the slideway and slide.

9. In a power head of the character described, a crank mechanism, a pitman operated thereby, a slide actuated by the pitman, a casing supporting said slide and enclosing said pitman and operating mechanism, said casing having an oil reservoir formed at the top thereof with spillways leading to the path of the slide and to the pitman connection between the pitman and slide, the lower part of the casing comprising an oil sump, an oil pump operated by the crank mechanism and an oil conduit extending from the oil pump to said reservoir.

10. In a power head of the character described, the combination of a casing, stud members secured to the casing and projecting inwardly in alignment, a double crank within the casing mounted on the stud members, a slide mounted on the exterior of the casing, a pitman in the casing mounted on the crank and swinging in a plane parallel to the plane in which the slide moves and connected with the slides by a wrist pin connection extending through a slot in the casing, a gear within the casing additional to the crank and tight with it, and a driving pinion meshing with the gear.

11. In a pump working head, the combination of an enclosed crank case adapted to hold lubricating oil, a crank mounted inside the crank case, means for rotating the crank, the crank case being adapted to hold oil at such level that the crank pin is immersed in the oil at each revolution, a crosshead guide housing mounted on the crank case, an oil cup in the top of the housing, vertical guides on the crosshead housing, a crosshead, a connection from crosshead to crank, a pump piston rod secured to the crosshead, a pump mounted inside the crank case and operated from the crank, an inlet to the pump below the top level of the oil, a discharge valve and valve chamber with a passage for carrying oil to the oil cup at the top of the crosshead guide housing.

12. In a pump working head, the combination of an enclosed crank case adapted to hold lubricating oil, a crank mounted inside the crank case, means for rotating the crank, a crosshead guide housing mounted on the crank case, an oil cup in the top of the housing, vertical crosshead guides on the housing, a crosshead, a connection from crosshead to crank, a pump piston rod secured to the crosshead, a reciprocating pump mounted inside the crank case and operated from the crank, an inlet opening to the pump beneath the oil top level, a discharge outlet pipe from the pump to carry oil to the oil cup at the top of the guide housing with oil channels from the oil cup to the crosshead guides and the top bearing of the connecting rod.

13. In a power head, the combination of an enclosed crank case adapted to hold lubricating oil, a crank mounted to rotate on bearings within the crank case, a crosshead, a crosshead guide housing, a connection from the crosshead to the crank, a gear wheel secured to the crank to rotate with it, a gear pinion to operate the crank gear, and a pinion shaft mounted in bearings having oil receptacles at their inner ends, a conical shape of the pinion shaft between the end of the pinion and one of the pinion shaft bearings with small end less than the bottom diameter of the pinion teeth space, the larger end about the diameter of the outside of the bearing and adapted to carry oil by centrifugal force from the gears to the bearing, there being means for keeping the oil level in the crank case so that some of the gear wheel teeth are always submerged in the oil.

14. In a power head of the character described, a crank mechanism, a pitman operated thereby, a slide actuated by the pitman, a casing supporting said slide and enclosing said pitman and operating mechanism, said casing having an oil receiver at the top with oil channels leading to the

path of the slide and to the pitman connection bearing of the slide, the lower part of the casing comprising an oil sump and means of maintaining the necessary depth of oil, an oil pump mounted inside the case and operated from the crank mechanism, an inlet to the pump cylinder below the top

level of the oil, a discharge valve and chamber with a pipe conduit extending up into the oil receiver at the top of the slide ways. 10

In testimony whereof, I hereunto affix my signature.

ALFRED RANDOLPH.
